UNITED STATES PATENT OFFICE.

FRANK PARDEE, OF HAZLETON, PENNSYLVANIA, ASSIGNOR TO ANTHRACITE SEPARATOR COMPANY, A CORPORATION OF PENNSYLVANIA.

SPIRAL-RUNWAY CONSTRUCTION.

Application filed October 28, 1921. Serial No. 511,210.

To all whom it may concern:

Be it known that I, FRANK PARDEE, a citizen of the United States, and resident of Hazleton, Pennsylvania, have invented certain new and useful Improvements in Spiral-Runway Constructions, of which the following is a specification.

This invention relates to improvements in construction of spiral structures and particularly to runways of substantially true spiral formation having an inwardly inclined surface. That is to say, considering a radial line on a spiral runway, a point at the outer or peripheral edge the surface is in a higher horizontal plane than that part of the surface which is near the axis of the spiral runway. Heretofore spiral runways of this class have been formed of a multiplicity of segmental plates or jackets having radial edges, the inner portions of said jackets being cut away to fit a central post by which the jackets are usually supported.

Plates having radial edges and inner cut away portions are more difficult to form and necessitate the expenditure of more labor and the waste of more material than plates or jackets constructed according to the present invention.

One object of the present invention is to provide a spiral runway made of a number of jacket sections which are adapted to engage the supporting post tangentially.

A further object is to provide a spiral structure comprising a number of jacket sections which need not be cut away to fit the central supporting post. A further object is to provide a jacket which can be produced at less expense than those heretofore proposed, but will serve its function equally as well. A further object is to provide a jacket which can be more readily and more truly warped or bent to conform to a true spiral surface than possible in structures heretofore used. Other objects will be apparent as the description proceeds.

The spiral runway herein described is particularly adapted for use on coal separators and the like but is not limited to such use as the following description will show that a spiral runway constructed according to the present invention can readily be adapted to many other uses.

The invention will be understood by reference to the accompanying drawings in which—

Fig. 1 is a side elevation showing three-quarters of a turn of a spiral runway constructed according to the present invention;

Fig. 2 is a top plan showing one complete turn of the runway;

Fig. 3 is a detail view of one of the jackets of the runway;

Fig. 4 is a plan view of a portion of a runway composed of a number of plates assembled in reverse position from that in which the plates are assembled in the structure shown in Fig. 2;

Fig. 5 is a plan view showing the position in which the jackets of Fig. 4 are turned before they are assembled;

Fig. 6 is a partial plan showing the tangential edges of the jackets of the runway closely fitting the sides of a central polygonal supporting post;

Fig. 7 is a detail of a jacket which is corrugated to form a friction surface.

Referring first to Figs. 1 to 3, the spiral runway comprises a multiplicity of component jackets 1 which are identical in shape and overlap one another along their adjacent edges. Each jacket 1 comprises a plate which is warped to correspond to a spiral surface and is formed with straight converging edges 2 and 3 and an outer edge 4 which may be curved as shown to conform substantially in plan view to a circle concentric with the axis of the central supporting post 5. Or if desired the outer edge 4 could be straight so as to form a runway having a polygonal periphery. The central post 5 carries a series of outwardly and upwardly extending rods 6 which are adapted to form supports for the several jackets 1. The edge 2 of each jacket is substantially tangent to the periphery of the post 5 and the edge 3 extends outwardly at an acute angle therefrom, the two edges intersecting at the apex 7 which is located a slight distance beyond the tangent point of contact of the edge 2 and the post, so that the interstices between the adjacent plates are practically closed, even though the edges 2 are straight and the post 5 is of substantially cylindrical formation.

I may however crimp up the portion of the

jacket near the apex so as to form a short flange 8 which may be on a radius equal to that of the supporting post so that the jacket will snugly fit the post at such location. Or 5 the post may be flattened at the points where the edges 2 contact with it. Or, as shown in Fig. 6, the post 5^a may be of polygonal formation having flat surfaces against which the tangential edges 2 of the jackets will snugly 10 fit.

In Figs. 1 and 2 the jackets are assembled so that the lower edge 3 extends beyond the upper edge 2 of the adjacent jacket forming a marginal overlap 9, best shown in Fig. 1. 15 It will be seen that as thus constructed the material in flowing down the runway from one jacket to another falls a distance equal to the thickness of one of the plates. As indicated by the arrow in Figs. 1 and 2, the 20 material flows clockwise, and the lower edge 3 is above the adjacent edge 2, so it is clear that the overlapping edges as thus assembled do not offer any resistance to the movement of the material traveling thereon. In these 25 figures the jackets are so assembled that the tangential edges 2 extend from a point at the periphery of the runway and downwardly to a point tangent with the surface of the supporting post. In other words, 30 considering a top plan view as in Fig. 2 the edges 2 are tangent and extend in a counter-clockwise direction from the circular surface of the central post 5. On the other hand, in Fig. 4 the plates are assembled in reverse 35 position to that shown in Fig. 2 so that their tangential edges 2 extend in clock-wise direction from the circular surface of the central post 5. This arrangement, therefore presents a marginal overlap 9^a which is inclined in the opposite direction from that 40 shown in Fig. 2. To express it in another way, the seam between the two adjacent jackets in Fig. 2 formed by the overlapping edges extends upwardly and outwardly from 45 the central post in counter-clockwise direction, whereas in the arrangement of Fig. 4 the two jackets extend upwardly and outwardly in a clockwise direction. When these 50 spiral runways are used in spiral separators for coal and like materials each arrangement has advantages for treating a particular class of material.

The runways constructed according to this invention may be used as simple conveyors or they may be effectively used as separator threads in spiral runways adapted to separate coal from slate and other impurities. Fig. 7 shows a jacket 1^a provided with a series of closely spaced ridges 10, adapted to jointly support the lumps of material which travel over the runway. These ridges are also adapted to exert an edge friction on the material and to control its direction of travel. They may be of various formation 60 to adapt them for producing the desired

effects on different classes of coal as disclosed in another application Serial Number 507,109 filed Oct. 11, 1921.

One advantage of forming the jackets with tangential edges as above described is 70 that it permits the use of simple plates which need not be cut away at the inner portion to fit the supporting post. It will be appreciated that this saves considerable time and therefore expense in the formation 75 of these jackets.

Those skilled in the art are aware that it is quite troublesome to cut away the inner portion of the segment or jacket so that a curve is produced which is an intersection 80 of the cylindrical part of the post and the warped spiral surface of the jacket. In other words in prior constructions in which the jackets were formed with edges radiating from the axis of the central post, it was 85 necessary to plot a curve on the inner portion of the jacket which in vertical projection would be a circle, yet one end thereof would be higher than the other. This curve of course is not a true circle but is a portion 90 of a sine curve or helix. With a post of comparatively small diameter it is quite difficult to plot these curves or make dies for cutting such curves, to produce a plate which will neatly fit the post at the center. 95 With the improved form of jacket shown herein, the cutting away of this central portion of the jacket is entirely eliminated as the edge 2 thereof extends tangentially outwardly from the surface of the supporting 100 post. It, therefore, only requires two cuts to form a jacket of the improved design. The edge 3 being the original edge of the stock from which the jacket is made and the edges 2 and 4 being the only ones that are 105 necessarily cut. The use of the flanged portion 8 is optional and is not absolutely necessary as it is apparent from the drawings that in the case of a cylindrical post the interstices of two adjacent jackets is so small 110 that they may be neglected and in the case of a polygonal post, Fig. 7, the adjacent jackets fit the post perfectly and do not leave any intervening spaces. Jackets of the shape shown are more easily assembled and 115 permit the formation of a much truer spiral or helical curve than that obtainable in jackets having truly radial edges. This is particularly true on the inner surface of the runway near the central post. Runways made up of jackets constructed as herein 120 described convey the material more uniformly and smoothly and with less agitation than possible with prior constructions.

The tangentially overlapping edges of 125 the plates effect a change in the position of the center of gravity of the descending pieces of material travelling down the runway, and thereby give a lateral impetus to said lumps. In a coal separator thread 130

this is of importance as it agitates the pieces and assists in the separation of the coal and slate. The separating or agitating effect on the material whereby the position of its center of gravity is changed by flowing over the tangential edges, differs from the effect produced by material flowing over jackets having radial edges. A lump of material falling over a tangential edge will tend to move in a direction normal to said edge and therefore it will turn or shift the location of its center of gravity and tend to move said lump outward when the plates are arranged as in Fig. 2 or inward as in Fig. 4. On the other hand when the edges overlap on a radial line there will be no lateral impetus given to the lumps when they pass over the seam as the radial edge is normal to the natural path of travel of the lumps.

While the spiral runway herein described is particularly adapted for use as a coal conveyor thread, or a coal separator thread, it is not to be interpreted that its use is restricted thereto as this construction could be applied to spiral runways used for various other purposes. And it is to be understood that the above specification and the accompanying drawings forming a part thereof are to be interpreted in an illustrative rather than a limiting sense, as modifications may be made without departing from the invention as defined in the appended claims.

35 What I claim is:

1. A spiral runway comprising a multiplicity of jackets whose surfaces are warped to form uniform continuous spiral surfaces, said jackets being of acute trian-

gular shape having converging edges, one 40 of said edges being substantially tangent to a circle concentric with the axis of the spiral runway.

2. A spiral runway including a central supporting post and a multiplicity of 45 jackets each having an edge which extends outwardly in a substantially tangential direction from said post, and radially extending rods carried by the post for supporting said jackets the tangential edge of each 50 jacket crossing at least two adjacent rods.

3. A runway including a central cylindrical supporting post having outwardly extending supporting rods and a multiplicity 55 of identical jackets of acute triangular shape, supported by said rods, the jackets being shaped to form a true warped surface, said jackets being secured to said post so that one edge is tangent thereto and extends in an upward and outward direction, the adjacent portions of said jackets overlapping one another to form a continuous runway having a constantly progressing warped spiral surface so that the material can travel thereon at a substantially 60 constant rate.

4. A spiral runway including a central supporting post and a multiplicity of jackets shaped to form a true warped surface 70 and being of acute triangular shape each having one edge substantially tangent to said supporting post and each jacket being formed with a flange on the tangent edge to fit the post, said runway having more than four jackets per turn.

In witness whereof, I have hereunto signed my name.

FRANK PARDEE.
